UNITED STATES PATENT OFFICE.

JOHN M. WADDELL, OF GREENFIELD, OHIO.

SHOW-CASE.

1,246,365.

Specification of Letters Patent.

Patented Nov. 13, 1917.

Application filed March 31, 1917. Serial No. 158,965.

To all whom it may concern:

Be it known that I, JOHN M. WADDELL, a citizen of the United States of America, and resident of Greenfield, in the county of 5 Highland and State of Ohio, have invented a new and useful Improvement in Show-Cases, of which the following is a specification.

My invention relates to a show case in 10 which the lid can not be opened by a person in front of the counter but must be released by a person behind the counter.

An object of my invention is a show case in 15 which the movement of the case by a salesman to a position in which its contents are readily accessible to the customer, simultaneously opens the lid.

Another object of my invention is a show case which has a lock which automatically 20 locks the lid and the case in their normal or closed position.

These and other objects are attained in the show case described in the following specification and illustrated in the accompanying drawings, in which:

Figure 1 is a perspective view of a show case embodying my invention.

Fig. 2 is an enlarged sectional view taken on the line 2—2 of Fig. 1.

Fig. 3 is a view similar to Fig. 2 but showing the case opened.

My improved show case consists of a base 4, a body 5 hinged to the base, a lid 6 hinged to the base, a link 7 operatively connecting 35 the lid and the body, and a lock 8 adapted to lock the lid and body in their closed positions. The base consists of end boards 9 and 10 connected by a brace 11 located beneath the body 5 of the show case. The body is 40 pivotally mounted by means of pins 12 secured therein and located in bearings formed in the end members of the base. The lid is similarly mounted by means of pins 13 journaled in bearings formed at the 45 tops of the end boards. Link 7 is pivotally connected with lid 6 at its rear edge by means of a pin 14 and with body 5 by means of a pin 15. This connection causes lid 6 to move to its elevated position as disclosed 50 in Fig. 3, when the body is moved from its normally inclined position to the less inclined position disclosed in Fig. 3. Lock 8 consists of a latch having one end 16 adapted to engage a bearing plate 17 secured to 55 the bottom of the body, the opposite end 16^a of the latch being formed to provide a

thumb piece to facilitate its operation. A spring 18 is provided for retaining the latch in its locked position as disclosed in Fig. 2. The lid may be provided with a glass covering 19 to enable the goods located in the body to be displayed to advantage.

When it is desired to gain access to the interior of the body 5, the operator's thumb is placed upon end 16^a of latch 8 to withdraw it from the position disclosed in Fig. 2 to that disclosed in Fig. 3.

Pressure upon the top edge of the lid and body of the case will then cause them to swing to the positions disclosed in Fig. 3, link 7 causing lid 6 to rise as the upper rear edge of the body is depressed. This renders the contents of the body accessible. As soon as the desired goods have been removed, the operator permits the case to close by releasing the pressure thereon, the weight of the lid acting to return the body to its normally inclined position. As soon as this occurs, latch 8 under influence of spring 18, returns to the position disclosed in Fig. 2, in which movement of the body to the position disclosed in Fig. 3, is an impossibility. Access to the interior of the body cannot even be gained by lifting upon the lower front edge of the lid since the rear upper edge thereof, being 55

upon the opposite side of pivot pins 13, bears downwardly upon the upper rear edge of the body and thus is obstructed in its movement because of abutting the end 16 of latch 8.

The show case illustrated is one adapted to display small articles, and is designed to be located in accessible and visible positions on larger show cases or counters, the front as viewed in Fig. 1, being toward the customer.

Having thus described my invention, what I claim is:

1. A show case comprising a base, a body pivotally mounted thereon and movable to 100 different positions relatively to the base, a lid pivotally mounted on the base, a link pivotally secured to the body and lid, adapted to move the lid in response to variations in the relative positions of the base and 105 body, and a lock adapted automatically to lock the case when the lid is in its closed position with relation to the body.

2. A show case comprising a base, a body pivotally mounted on the base and adapted 110 to occupy a normally inclined position, a lid pivotally mounted on the base and

adapted to close the body in its normally inclined position, means operatively connecting the lid and body, adapted to be actuated by variations in the relative positions of the base and the body, for actuating the lid, and a manually released lock adapted automatically for locking the body in its normally inclined position on the base and for thereby locking the lid in its closed position.

3. A show case comprising a base, a body pivotally mounted thereon and movable to different positions relatively to the base, a lid pivotally mounted on the base, a link pivotally secured to the body and lid, adapted to move the lid in response to variations in the relative positions of the base and body, and a lock adapted automatically to lock the case when the lid is in its closed

position with relation to the body, said lock 20 consisting of a lever pivotally mounted on the base, between its ends and adjacent to the body, and a spring normally tending to bring the lever to a vertical position with relation to the bottom of the body and into 25 engagement therewith, the opposite end of said lever being adapted to be engaged by one's thumb to remove the lever from its locking position to permit the body to be moved to open the case. 30

In testimony whereof, I have hereunto subscribed my name this 29th day of March, 1917.

JOHN M. WADDELL.
